UNITED STATES PATENT OFFICE.

GEORGE W. BEADLE, OF STAMFORD, CONNECTICUT, AND SAMUEL KOHN, OF NEW YORK, N. Y., ASSIGNEES TO COLUMBIA GRAPHOPHONE MANUFACTURING COMPANY, OF BRIDGEPORT, CONNECTICUT, A CORPORATION OF DELAWARE.

AUTOMATIC STOP.

Application filed September 6, 1919. Serial No. 322,180.

To all whom it may concern:

Be it known that we, GEORGE W. BEADLE and SAMUEL KOHN, citizens of the United States, and residing, respectively, at Stamford, county of Fairfield, and State of Connecticut, and city, county, and State of New York, have invented certain new and useful Improvements in Automatic Stops, of which the following is a full, clear, and exact description.

The invention which constitutes the subject matter of this application has to do with improvements in automatic stop mechanism especially designed for a talking machine, which ordinarily has a rotating record support or member and a traveling member, as a sound-box and tone-arm, said rotating member and traveling member being relatively movable, the latter being commonly fed relatively to the former by the co-action of the needle of the sound-box with the record groove. This invention embodies improvements contained in our copending application Ser. No. 310,912, filed July 7, 1919.

One of the most important features of our invention consists in improved mechanism whereby the actuation and the starting of the mechanism from and the stopping of the same at any position is controlled solely by the movement of the reproducer or traveling member. The construction is such that the machine will be automatically started when the operator places the reproducer and tone-arm in position to commence reproduction; will be automatically stopped when the reproducer member shall cease its advance movement across the face of the record, will remain at rest as the reproducer member is being returned to the position of "rest" beyond the edge of the record; and will be automatically started when the reproducer member is moved from its position of "rest" to the position for commencing the reproduction of the record.

Another important feature of this invention consists in providing mechanism with improved means which will not only enable the starting of the mechanism automatically when the reproducer member is placed above the position to commence the playing of the record, but which will effectively prevent the mechanism controlled by the reproducer member from becoming operatively related to the automatic stop mechanism so long as

the reproducer member remains in this position irrespective of the number of revolutions of the rotating member made while in this position. In other words the mechanism controlled by the rotating and traveling member for actuating the stop mechanism is so constructed as to become operatively related to said stop mechanism only after the traveling element has moved inwardly for a predetermined distance across the face of the record.

Stop mechanisms heretofore devised for accomplishing stated objects have been more or less complicated in construction. A still further feature of our invention therefore resides in the fact that we have not only made the device entirely automatic but reduced the number of parts, made it more positive in operation and cheapened its cost of manufacture.

Further objects and advantages will appear from the detailed description below taken in connection with the accompanying drawing in which,

Fig. 1 is a top plan of the invention showing its application to the motor board of a conventional form of talking machine, the parts being in normal or rest position with the reproducer sound-box beyond the edge of the record.

Fig. 2 is a bottom plan view of the invention in normal position.

Fig. 3 is a section taken on the line 3—3 of Fig. 1.

Fig. 4 is bottom plan view of certain parts illustrated in a different position from that shown in Figs. 1 and 2.

Figs. 5 and 6 are details of parts of the automatic stop mechanism.

Fig. 7 is a longitudinal section of the tone-arm base and the friction mechanism associated therewith.

Figs. 8 to 12 inclusive illustrate detail elements.

Referring to the drawings in detail, the reference numeral 10 (see Fig. 3) designates the top of a conventional form of phonograph cabinet having a centrally located opening 11 to provide convenient access to the motor 12, and also to receive the elements which establish communication between the sound reproducing member and the sound amplifying instrumentalities. The opening 11 is closed by the hinged mo-

tor board 13, preferably made of metal and of the usual construction. Located above the motor board 13 is a turntable 14 supported upon a rotating spindle 15, and positioned upon the turntable is a conventional form of record disc 16. Positioned above the record disc 16 and motor board 13 is a tone arm 17 provided with a sound-box 18, said tone arm and sound box being generally referred to herein as a traveling member. The tone arm is swiveled to the laterally extending portion of the elbow member 19 to enable it to be raised and lowered with respect to the sound record. The elbow member is provided with an annular shoulder 20 (see Figs. 3 and 7) and a downwardly extending portion 21, the former of which rests upon and the latter of which is swiveled to the base member 22, thus enabling the tone arm to oscillate in a horizontal direction over the sound record. A lock screw 23 in the base member 22 engages with a horizontal slot 24 in the swiveled portion 21 to enable relative rotation, but preventing relative longitudinal movement of the base and elbow members. The foregoing parts are all broadly old and well known and are therefore no part of our invention, except as they constitute a part of the combination defined by the appended claims.

The turn-table spindle 15 projects upwardly through a perforation 25 in the motor board 13. On this spindle, preferably located below the motor board is fixed a pinion 26 which meshes with a gear 27 rotatably mounted upon a stud 28 secured to and projecting downwardly from the motor board. Fixed to this gear 27 in any suitable fashion is an eccentric cam member 29 so constructed that during the rotation of the gear 27 the face of this cam engages with the anti-friction roller 30 mounted upon stop member 31, the latter being pivotably mounted below the motor board. About the pivot 32 of the stop member is wound a spring 33 one end of which bears against the member and the other end of which bears against a fixed stud 34 on the motor board with a result that the spring 33 always tends to move the stop member 31 in a clockwise direction about its pivot thereby tending to maintain the anti-friction roller 30 in contact with the face of the eccentric cam 29 during the rotation of the rotating spindle.

Pivoted at 35 to the lower side of the motor board is a brake member 36 the downwardly projecting arm 37 of which (see Fig. 3) is provided with a friction pad 38 adapted to engage any movable part of the machine preferably the governor disc 39 of the motor. The other end of this member has an operative connection with one end of a member 40, the other end of the latter being provided with a guide slot 41 engaged by a

guide stud 42 on the motor board to enable the said member 40 to slide longitudinally, the reasons for which will more fully appear hereinafter. At the extreme end of the member 40 adjacent the slot 41, there is provided a lip or stud 43 adapted to be engaged by a lever 44, the purpose, construction and operation of which will be more fully described hereinafter. At its intermediate portion the member 40 is also provided with a stud 45 adapted to engage the outer end of the stop member 31. Pivoted at 46 to and located below the motor board 13 is a latch member 47 having a lip 50 engaged by the end of a follower flange 55 frictionally movable with the tone-arm in a manner to be presently more fully described, to move the latch member in clockwise direction when not otherwise opposed. The free end of the latch member 47 is provided with a pocket and a projecting hook portion 48 having its end adjacent the pocket tooth-shaped, and which by the movement of the traveling element is moved in the path of stud 49 of the stop member 31 the stud having a complementary tooth-shaped lower edge which lockingly engages the hook portion 48 on each inward oscillation of the latter as the traveling element is feeding inwardly across the record, thereby limiting the clockwise movement of the stop member and thus preventing the application of the brake. The latch member is provided with a cam surface 51, engageable by stud 49, as the stop member 31 is oscillated in an anti-clockwise direction so as to move the latch 48 in contra-clockwise direction out of the path of said stud 49 and against the frictional propelling force of the tone-arm as it moves in clockwise direction.

From the foregoing it will be apparent that each time the stop member 31 is oscillated by the cam 29 in a counter-clockwise direction while the record is being played, an oscillatory impulse is imparted to the latch member 47 moving the latter also in a counter-clockwise direction about its pivot so as to move the latch 48 out of the path of the stud 49. And as long as the traveling member is moving inwardly across the face of the record, mechanism is employed for imparting an alternate impulse to the latch member to move the latter back into the path of the stud 49 and preventing the application of the brake, it being understood that as soon as the inward movement of the traveling member across the face of the record ceases the latch 48 will remain out of the path of the lug 49, thus enabling the application of the brake. Any suitable mechanism for imparting clock-wise impulses to the latch member 48 may be employed, one form of which we will now proceed to describe.

The tone-arm base or support 22 is

mounted on the motor board 13 by suitable, preferably concealed, screws 52 (see Fig. 7) and is provided with a skirt 53 having a circumferential slot 54 in the side facing the record to permit the elements controlling the stop mechanism to project therefrom. One of the edges of this opening serves to maintain the end of a follower finger, to be described, within a limited distance of the 5 lip or pusher surface 50 of the latch member. The member 21, which preferably rotates about a vertical axis, as previously described, is provided with a downwardly projecting sleeve 55, which is provided (see 10 Figs. 7 and 8) with a plurality of circumferentially disposed bayonet slots 56 and a vertically disposed key 57. An annular spring retaining member 58 having a plurality of inwardly projecting radial lugs 59 15 is adapted to lock with the sleeve 55, the lugs 59 thereof engaging and locking with the bayonet slots when in operative position as will be readily understood. A plurality of superposed friction discs surround the 20 sleeve 55 and serve to operate the stop releasing mechanism through the rotation of the traveling element. The upper one of these discs (see Fig. 9) designated by 60 has formed on its periphery a lug 61 25 adapted, when the tone-arm is brought to its initial position, to release the stop member and permit the turn-table to rotate, and is also provided with a notch or keyway 61 engaged by the key 57 so that it rotates 30 as a unit with the sleeve 55. The inner periphery of the intermediate friction disc 63 35 is cleared away at 64 so as to permit the follower finger 65 to remain unaffected by the movement of the key 57; that is to say, 40 it enables said key to move back and forth therein. A third disc 66 is located below the intermediate disc 63 and is provided with a keyway for the key 57 so that it also rotates as a unit with the skirt 55. The three 45 friction discs are maintained in intimate contact with each other by a spring 68 (see Fig. 7) having its lower end engaging the annular spring retaining ring 58 and with its upper end bearing against the lower 50 surface of the friction disc 66. The intermediate friction disc 63 has secured thereto preferably integral therewith the follower finger 65, the curved end of which is adapted to engage the depending pusher surface 50 55 of the latch member 47. This disc 63 and finger 65 we shall hereinafter refer to as the "follower member." The specific mechanism just described for effecting a frictional engagement with the follower member 60 is merely the preferred form and it is therefore to be expressly understood that we do not confine ourselves thereto. The construction of this mechanism is more fully illustrated in our copending application 65 above referred to.

The follower member, due to its frictional engagement with discs 60 and 66, as the traveling member feeds across the record, tends to rotate the latch member 47 in a clockwise direction causing the surface 51 70 to bear against the stud 49 of the stop member 31. As the latter is moved outwardly by the cam 29 against the action of the spring 33, as it does once for each complete rotation of said cam 29, the stud 49 co-operating 75 with the cam surface 51, oscillates the lever in a counter-clockwise direction to a point where the latch 48 is out of the path of the stud 49 as previously explained. This movement of the latch member in turn im- 80 parts a correspondingly counter-clockwise movement to the follower member. As the bearing roller 30 moves from the high towards the low point of the cam 29, thus enabling the inward oscillation of the stop member, the follower member will be moved 85 in a clockwise direction by virtue of its frictional engagement with the moving tone-arm, imparting at the same time, a corresponding clockwise movement to the latch 90 member 47, these movements being so correlated that before the stop member 31 arrives at a predetermined point the latch 48 will be located in the path of the stud 49, thereby limiting the inward movement 95 of the stop member. In point of fact the specified construction herein illustrated is such that the movement of the latch member 47 by the follower member will effect a constant engagement of the stud 49 from the 100 high to the low point of the cam surface 51 as the stop member 31 is moved inwardly under the tension of the spring 33. When the traveling element ceases to feed across the record, which will take place when the 105 needle of the tone-arm reaches the last groove in the record disc, obviously the follower member, no longer forces the latch 48 inwardly into the path of the lug 49, thus enabling the roller 30 to ride down the 110 receding incline on the cam 29 until the stop member 31, under the force of the spring 33, has moved inwardly a sufficient distance to actuate the slide 40 and brake member 36 and cause the friction member 38 on said 115 brake member to engage with and stop the rotation of the motor.

Pivoted between its ends at 67 to the motor board 13 is the lever 44 provided on one end with a pivoted cam 68 adapted to 120 be actuated by the camming member 61. The other end of the lever 44 is provided with an operating nose adapted to engage the inner surface of the upstanding flange 43 of the sliding bar 40. The actuation by 125 the camming member 61 of the pivoted cam 68, as the tone-arm is moved from its position of non-playing or "rest" indicated in Fig. 1 to the position where the instrument starts to play the record, oscillates the lever 130

44 about its pivot 67 in a counter-clockwise direction, thereby moving the brake member 36 to release the motor. A spring 70 normally maintains the cam 68 in the position illustrated in Figs. 1 and 2 so that the tone-arm may be returned to its non-playing or normal position without actuating the lever 44. When it is desired to operate the talking machine without the automatic stop mechanism, it is only necessary to move the lever 71 in a counter-clockwise direction about its pivot 72 to its other extreme position. This disengages the roller 30 from the cam 29 and hence the stop member 31 remains stationary during the rotation of the turn-table. When it is desired to operate the machine with the automatic stop mechanism functioning, the lever 71 is moved to the position illustrated in Fig. 1. The spring 33 then retracts the stop member 31 so that the roller 30 engages the cam 29. This is merely the preferred form of construction for rendering the non-set stop device disorganized or inoperative, and it is therefore to be understood that we do not limit ourselves specifically thereto. When the automatic stop mechanism is rendered inoperative the machine is controlled in the usual way by lever 73.

5 The point of the inclined portion of the cam 29 which strikes the roller 30 upon each rotation of the former is provided with a yielding surface 74 for cushioning the impact thereby avoiding a click that would occur in case of a metal-to-metal contact of cam 29 and roller 30.

40 The operation is as follows:—Let it be assumed that the traveling member is carried beyond the edge of the turn-table to the position of rest, as is the case when a record is to be changed or replayed, as illustrated in Fig. 1. In this position of the sound reproducer and its appurtenant elements, the 45 lug 61 (see Fig. 1) is located in a counter-clockwise position with respect to the cam member 68 on the end of the lever 44. The follower finger 65 of the follower member 63—65 in the supposed position bears 50 against the edge 75 of the circumferential slot 54 having been brought to this position by virtue of the frictional engagement of its disc with discs 60 and 66, in the movement of the sound reproducer backwardly 55 over the face of the record. The relative position of the other elements will be apparent from a casual inspection of Figs. 1 and 2. As the traveling element is being brought to the position where the reproducer needle engages the record groove at 60 the beginning of the record, the lug 61 engages the cam 68 and oscillates the lever 44 against the tension of the spring 53. This releases the brake pad 38 from the edge of 65 the disc 39 and permits the latter to rotate.

At this moment the position of these parts is clearly illustrated in Fig. 4. The movement of the tone-arm from its position of rest to the position where the needle engages the record groove causes the outer 70 end of the follower member to engage with the web 50 of the latch member 47, the latter being substantially at its extreme point of movement in a counter-clockwise direction, it being of course understood that its movement in this direction is preferably limited by the engagement of the web 50 with the nose of the follower member. As the traveling member feeds across the record, the lug 61 passes the cam 68 on the end 75 of the lever 44 and permits the latter to take its normal position corresponding to its position shown in Fig. 1 and in which it is inoperative to retain the brake released. It will be seen however that before the lug 61 passes the cam 68 the operation of the follower member and latch member, though idle, is taking place, but these members only begin to function after the said cam 61 passes slightly beyond the dead center of 80 said cam 68. Consequently there is no possibility at this time of the stop member functioning as such, since its first inward movement is arrested or "limited" by the 85 automatic positioning of the latch 48 behind the lug 49 in the manner previously explained. This does not necessarily mean however that the "first" inward movement of the stop lever is arrested by the latch member 47, as it will be readily apparent, 90 depending upon the correlative position of the cam lug 61 and cam wheel 29, that the roller 30 will contact with the said cam wheel 29 in advance of the engagement of the stud 49 with the latch 48. The point is 95 that during the first few rotations of the record disc the stop member is held out of its operative position by the lever 44 and its co-operating cam lug 61, and that at any predetermined point thereafter this particular work of the lever 44 is effected by the follower member 63—65 and the latch member 47. The rotation of the spindle and its pinion 26, during the reproduction of the record, causes a rotation of the gear 27 and 100 its attached cam or eccentric 29. The rotation of the eccentric by engagement of its periphery with the roller 30 on the stop member 31 causes the latter to oscillate. The outward oscillations of this member 105 force the hook portion 48 of the latch member out of the path of the stud 49. While the tone-arm and its reproducer are feeding across the record, the follower finger 65, by frictional engagement of its disc 63 with the other discs, engages with the surface 50 and tends to rotate the latch 47 in a clockwise direction. This alternate 110 clockwise impulse imparted to the latch member maintains the engagement of cam 115 120 125 130

surface 51 with the lug 49 on each inward oscillation of the stop member 31, thereby preventing the brake pad secured to the brake member from engaging the turn-table. 5 When, however, the tone-arm reaches the end of the record, the clockwise impulses of the follower member and of the latch member are discontinued, and the latch 48 secured to the end of the latch member and 10 moved out of the path of the stud 49 on the outward reciprocation of the brake member, is not thereafter forced into the path of stud 49 on its inward reciprocation, thus causing the brake pad attached to the arm 15 37 of the brake member 36, under the influence of the spring 33, to engage the disc 39 and stop its rotation. When it is desired to either reproduce the same record or to reproduce another record, the traveling member 20 is again swung to its initial position beyond the edge of the turn-table, as illustrated in Fig. 1, the follower finger being prevented during this movement from following the traveling member beyond a pre- 25 determined point, by its engagement with the edge of the circumferential slot 54 at the lower end of the tone-arm. When the reproducer needle is placed on the record the lug 61 again engages the arm 68 and re- 30 leases the motor, permitting a repetition of the operation above described.

When the lever 71 is moved to its other extreme position from that illustrated in Fig. 1, its hooked inner end engages with 35 the lug 49 and cams the stop member 31 in a counter-clockwise direction about its pivot, thereby moving the end of the latter out of operative contact with the lip 45 of the member 40, thus rendering the automatic 40 mechanism inoperative but enabling freedom of action of the manual lever 73 to operate the brake member 36.

The stop member 31 is shown herein as connected to the brake member 36 by means 45 of the slidable member 40. It may be stated, however, for manufacturing and other reasons, that this is merely the preferred form of construction and that we therefore do not limit ourselves to the specific connection nor do we limit the invention 50 to a brake member which engages the governor disc of the motor.

The stop member 31 is illustrated in the accompanying drawings as operating a 55 brake but it is to be expressly understood that our invention is not limited thereto as the stop element in question may be employed to operate a contact to start and stop an electrical motor. And it may also 60 be stated in this connection that while the embodiments of the invention illustrated in the drawings have been described with considerable particularity, it is to be further understood that we do not limit ourselves thereto, as many changes may be made in 65 point of detail and other embodiments resorted to without deviating from the true spirit and scope of our invention as defined by the appended claims.

What we claim is:—

1. In combination, a traveling member, a rotating member, means for actuating the rotating member, an oscillating stop member actuated by said means and adapted to cause stoppage in one direction of oscillation, and means cooperating with the stop member for limiting its oscillations in stopping direction to prevent stopping, and acting when the traveling member stops to render operative the stop member. 70

2. In combination, a traveling member, a rotating member, means for actuating the rotating member, and means acting when the traveling member ceases to move to stop the rotating member, comprising an oscillating stop member, means actuated by the movement of the traveling member to limit the oscillations of the stop member in one direction, said last-mentioned means being rendered inoperative by the oscillation of the stop member in the other direction when the traveling member ceases to move, thereby rendering operative the stop member. 80

3. In combination a traveling member, a rotating member, means for actuating the rotating member, and means acting when the traveling member ceases to move to stop the rotation of the rotating member comprising a stop member, means for imparting oscillating impulses to the stop member, and means rendered operative by the movement of the traveling element for limiting the impulses in one direction but rendered inoperative by the stop member when the movement of the traveling member ceases to enable the stop member to become effective. 95

4. In combination, a traveling member, a rotating member, means for actuating the rotating member, and means acting when the traveling member ceases to move to stop the rotation of the rotating member comprising an oscillating stop member, means for imparting oscillating impulses to the stop member, means rendered operative by the movement of the traveling element for limiting the impulses in one direction, and means associated with the stop member adapted to render the said means inoperative whenever the movement of the traveling member ceases, thereby enabling the stop member to 110 continue its otherwise limited movement to effective position.

5. In a stop mechanism, the combination with two independently moving members, of a stop member, means for imparting oscillatory impulses to the stop member, means rendered operative by the movement of one of said moving members for limiting the impulses of the stop member in one direction, but rendered inoperative by the stop member 125 130

when the movement of said member ceases to enable the continuation of its movement to effective position to stop the other member.

6. In a stop mechanism, the combination 5 with two independently moving members, of a stop member, means for imparting oscillatory impulses in opposite directions to the stop member, means rendered operative by the movement of one of the members for 10 limiting the impulses of the stop member in one direction, and means associated with the stop member for rendering said means inoperative when the movement of said last mentioned moving member ceases, thereby 15 enabling the stop member to continue its movement to effective position.

7. In a stop mechanism, the combination 20 with two independently moving members, of a stop member, means for oscillating the stop member in opposite directions to enable it to start and stop one of said moving members and means rendered operative by the movement of the other moving member for limiting the movement of the stop member towards its stopping position.

8. In a stopping mechanism, the combination 25 with a traveling and a rotating member, of a brake member for one of said members, a stop member operatively connected to the brake member, mechanism for moving the stop member in opposite directions to cause 30 the brake device to engage and disengage one of said rotating members, means rendered operative by the movement of the other member for limiting the movement of the stop member towards its stopping position, and means associated with the stop member adapted to render said means inoperative 35 when the movement of the traveling member ceases, thereby enabling said member to 40 continue its movement to stopping position.

9. In a brake mechanism, the combination 45 of a rotating member and a traveling member, a stop member for the rotating member, a brake member operatively connected to the stop member, means for imparting impulses in opposite directions to the stop member, whereby the brake member is adapted to be engaged with and disengaged from the rotating member, and means controlled by the movement of the traveling member and the stop member to limit said impulses of the latter towards 50 stopping position, said controlling means being rendered ineffective to limit the movement of the member when the movement of the traveling member ceases.

10. In a brake mechanism, the combination 55 with a rotating member and a traveling member, of an oscillating stop member, a brake element operatively connected to the stop member, and means actuated by the rotating and traveling members for control-

65 ling the brake element comprising mechanism for oscillating the stop member, a latch actuated by the traveling member to limit the oscillation of the stop member towards its operative position, the latch being rendered inoperative by the oscillation of the 70 brake element in the opposite direction to enable the stop member on its next oscillation to move the brake element to operative position.

11. In combination, a rotating member, a 75 traveling member, a stop member, means operatively connected to the rotating member for oscillating the stop member intermittently in opposite directions, mechanism operatively connected to the traveling member for limiting the movements of the stop member in the direction of its stop-actuating position, said mechanism being rendered inoperative by the movement of the stop member in the opposite direction and the stopping 80 of the movement of the traveling member.

12. In combination, a rotating member, a traveling member, a stop member, means operatively connected to the rotating member 85 for oscillating the stop member intermittently in opposite directions, mechanism actuated by the movement of the traveling member for limiting the movements of the stop member in the direction of its stop-actuating position, said mechanism being moved to inoperative position by the movements of the stop member in the opposite direction to enable the stop member to move 90 supplementally to stop actuating position 100 when the movement of the traveling member ceases.

13. In combination a rotating member, a traveling member, a stop member means for oscillating the stop element intermittently 105 towards and from its stop-actuating position, mechanism actuated by the movement of the traveling member for limiting said movement of the stop element towards stop-actuating position, said mechanism being 110 moved to inoperative position by each movement of the stop member from its stop actuating position to enable the stop member to move supplementally to stop-actuating position 115 when the movement of the traveling member ceases.

14. In combination a rotating member, a traveling member, a stop member, means for oscillating the stop element intermittently towards and from its stop-actuating 120 position, mechanism co-operating with and controlled by the movements of the traveling member and the stop member for limiting the movements of the stop member towards stop-actuating position, and means 125 for rendering said mechanism inoperative by the movement of the stop member from its stop-actuating position to enable said

stop member to move to stop-actuating position when the movement of the traveling member ceases.

15. In combination a rotating member, a traveling member, a motor for said rotating member, a stop member, means comprising a cam operated by the motor for oscillating the stop member intermittently from and towards its stop-actuating position, said 5 cam being provided with a high and a low point to enable the stop member to be moved from and to its stop-actuating position, mechanism actuated by the movement of the traveling member for limiting the movements of the stop member towards stop-actuating position, the mechanism being rendered inoperative by the movements of the stop member from its stop-actuating position to enable the stop member to move to 15 stop-actuating position when the movement of the traveling member ceases.

16. In combination a rotating member, a traveling member, a stop member, and means co-operating with the stop member 25 and acting when the traveling member stops to render operative the stop member comprising means for imparting oscillatory impulses to the stop element towards and from its stop-actuating position and controlling 30 means successively moved to operative position to limit said impulse towards stop-actuating position and to inoperative position to enable the stop member to move supplementally when the movement of the traveling member ceases.

17. An automatic stop mechanism for talking machines actuated by the rotating and traveling member comprising a movable cam and a member periodically contacting with and actuated by the cam, the point 40 of contact of the cam with said member being provided with cushioning means.

18. In a talking-machine having a rotating element and a traveling element, stop 45 mechanism actuated by said elements, and including brake mechanism, a brake-actuating lever, a cam controlled by the rotating element adapted to permit movement of the brake-actuating lever to brake-actuating position, and means adapted to restrain such movement during movement of the traveling element, and adapted, upon stopping of the traveling element, to permit such movement of the brake-actuating lever.

19. In a talking-machine having a rotating element and a traveling element, stop mechanism actuated by the rotating element and the traveling element and including 55 stopping means, a stop-actuating lever, a cam controlled by the rotating element adapted to permit movement of the stop-actuating lever to stop-actuating position, and means adapted to restrain such movement during movement of the traveling ele-

ment, and adapted, upon stopping of the traveling element, to permit such movement of the stop-actuating lever.

20. In a talking-machine having a rotating element and a traveling element, stop mechanism including a brake lever, an actuating member for the brake lever, means for permitting movement of the actuating member to its brake lever actuating position, and means to restrain such movement during the traverse of the traveling element, and adapted to permit such movement upon the stopping of the traveling element.

21. In a talking-machine having a rotating element and a traveling element, stop mechanism including stopping means, means for 80 permitting movement of the stopping means to its stopping position, and a movable latch member adapted to restrain such movement during the traverse of the traveling element and adapted to permit such movement upon 85 the stopping of the traveling element.

22. In a talking-machine having a rotating element and a traveling element, stop mechanism including brake mechanism, a brake-actuating lever, means for permitting 90 movement of the brake-actuating lever to brake-actuating position, and means to restrain such movement during the traverse of the traveling element, and adapted to permit such movement upon the stopping of the 95 traveling element.

23. In combination, a traveling member, a rotating member, an oscillating stop member actuated by said means, adapted to cause stoppage in one direction of oscillation, 100 means cooperating with the stop member for limiting its oscillation in stopping direction to prevent stopping, and acting when the traveling member stops to render operative the stop member, and a brake element connected to and actuated by the stop member when the latter is moved to stopping position.

24. In combination, a traveling member, a rotating member, means for actuating the 110 rotating member, an oscillating stop member actuated by said means and adapted to cause stoppage in one direction of oscillation, means cooperating with the stop member for 115 limiting its oscillation in stopping direction to prevent stopping, and acting when the traveling member stops to render operative the stop member, brake mechanism, and means for establishing connections between the stop member and brake mechanism only 120 when the stop member is moved to stopping position.

25. In combination, a traveling member, a rotating member, stop-actuating means adapted to be moved to stopping position 125 upon cessation of movement of the traveling member, brake mechanism, and means for establishing connections between said stop-

actuating means and brake mechanism only when the stop-actuating means is moved to stopping position.

26. In combination, a traveling element, a rotating element, stop mechanism, a member adapted to actuate the stop mechanism to stopping or non-stopping position, means cooperating with the rotating element to move the member to stopping position, and means cooperating with the traveling element to move the member to non-stopping position. 70

27. In combination, a traveling element, a rotating element, stop mechanism, a member adapted to actuate the stop mechanism to stopping or non-stopping position, means cooperating with the rotating element to move the member to stopping position, and means cooperating with the traveling element to move the member to non-stopping position as the traveling element is moved inwardly to the initial playing position. 75

28. In combination, a traveling element, a rotating element, stop mechanism, a member adapted to actuate the stop mechanism to stopping or non-stopping position, means cooperating with the rotating element to move the member to stopping position, and a lug movable with the traveling element to cooperate with the member to move it to non-stopping position as the traveling element is moved to initial playing position. 80

29. In combination, a traveling element, a rotating element, stop mechanism, a member adapted to actuate the stop mechanism to stopping or non-stopping position, means cooperating with the rotating element to move the member to stopping position, a lug movable with the traveling element adapted to cooperate with the member to move it to non-stopping position as the traveling element is moved to initial playing position. 85

30. In combination, a traveling element, a rotating element, stop mechanism, a member adapted to actuate the stop mechanism to stopping or non-stopping position, means cooperating with the rotating element to move the member to stopping position, a lug movable with the traveling element adapted to cooperate with the member to move it to non-stopping position as the traveling element is moved to initial playing position, the lug adapted to remain in cooperation with the pivoted member as the traveling element is disposed within a substantially annular area inwardly of the initial playing position, and adapted through such cooperation to prevent actuation of the member to stopping position. 90

31. In combination, a traveling element, a rotating element, stop mechanism, a member cooperating at one end with the stop mechanism to actuate it to stopping or non-stopping position, means cooperating with the rotating element to move the member to

stopping position, and means movable by the traveling element adapted to cooperate with the other end of the member, and actuated to non-stopping position as the traveling element is moved to initial playing position. 95

32. In combination, a traveling element, a rotating element, stop mechanism, a member adapted to actuate the stop mechanism to stopping position, an oscillating member actuated by the rotating element and adapted in one direction of movement to engage the member to move it to stopping position, and means cooperating with the oscillating member to maintain it in its non-stopping position while the traveling element is traveling. 100

33. In combination, a traveling element, a rotating element, stop mechanism, an actuating member therefor, a follower finger frictionally driven by the traveling element, a latch actuated by the finger to engage the stop-actuating member, the follower finger adapted to move the latch into position to limit each movement of the stop-actuating member in stop-actuating direction while the traveling element travels, and means adapted to prevent the locking of the latch therewith when the traveling element has stopped to permit the stop mechanism to 95 operate. 105

34. In combination, a traveling element, a rotating element, stop mechanism, a stop-mechanism-actuating member, a follower finger in frictional engagement with the traveling element, means cooperating with the rotating element to oscillate the actuating member, a pivoted latch adapted to lock the actuating member in non-stopping position, means cooperating with the rotating element to oscillate the actuating member, and means adapted to maintain the latch in locking engagement with the actuating member while the traveling element is traveling and adapted to release the actuating member when the traveling element ceases to travel. 110

35. In combination, a traveling element, a rotating element, stop mechanism, a stop-mechanism-actuating member, a follower finger in frictional engagement with the traveling element, means cooperating with the rotating element to oscillate the actuating member, a pivoted latch having a locking portion and a camming portion, the locking portion adapted to prevent movement of the actuating member to stopping position, the camming portion adapted, as the actuating member is oscillated away from stopping position, to move the locking portion of the latch out of locking relation with the actuating member, and means adapted to engage the latch in locking engagement with the actuating member while the traveling element is traveling and adapt- 115 120 125 130

ed to release the actuating member when the traveling element ceases to travel.

36. In a stop mechanism, the combination with two independently moving elements, of 5 stop means and an actuating member therefor, means for imparting impulses to the actuating member, means rendered operative by the movement of one of the elements for limiting the impulses of the actuating member in one direction, but rendered inoperative by the actuating member when the movement of such element ceases, to enable the continuation of its movement to effective position to actuate the stop means.

15 37. In a stop mechanism, the combination with two independently moving elements, of stop means and an actuating member therefor, means for imparting impulses in opposite directions to the actuating member, 20 means rendered operative by the movement of one of the elements for limiting the impulses of the actuating member in one direction, and means associated with the actuating member for rendering the next-above- 25 mentioned means inoperative when the movement of the element ceases, thereby enabling the actuating member to continue its movement to effective stopping position to stop the movement of the other moving 30 element.

38. In a brake mechanism, the combination with a traveling element, and a rotating element, of a brake element, an oscillating member operatively related to the brake 35 element, means associated with the traveling element and rotating element for controlling the brake element, comprising mechanism for oscillating the oscillating member, and a latch actuated by the traveling 40 element, to limit the movement of the oscillating member toward its operative position, the latch being rendered inoperative by the oscillation of the brake element in the opposite direction, to enable the oscillating member 45 on its next oscillation to move the brake element to operative position.

39. In combination, a traveling element, a 50 rotating element, a cam for actuating the rotating element, a brake-shoe adapted to stop the motor and to be moved to permit starting, a member cooperatively related to the brake-shoe member and adapted in one direction to move it to stopping position, and in its other direction to release it, means 55 adapted to automatically move the member to stopping position upon the stopping of the traveling element, eliminator means adapted to render the automatic means inoperative, and manually operating means 60 adapted to actuate the brake-shoe independently of the automatic means.

40. In combination, a traveling element, a 65 rotating element, a motor for actuating the rotating element, including a governor having a movable speed regulating part, a brake-

shoe member adapted to engage this part to stop the motor and to be released therefrom to permit starting, an actuating member cooperative with relation to the brake-shoe member and adapted in one position to move 70 it to starting position, and in its other position to release it, means adapted to automatically move the actuating member to stopping position upon the stopping of the traveling element, and eliminator means 75 adapted to render the automatic means inoperative and permitting the manual operation of the brake-shoe member.

41. In combination, a traveling element, a 80 rotating element, a motor for actuating the rotating element, start and stop mechanism for the motor, a start and stop member cooperatively related thereto and adapted in one position to actuate it to stopping position, and in its other position to actuate it 85 to starting position, and means adapted to automatically move the start and stop member to stopping position upon the stopping of the traveling element.

42. In combination, a traveling element, a 90 rotating element, a motor for actuating the rotating element, start and stop mechanism for the motor, a start and stop member cooperatively related thereto and adapted in one position to actuate it to stopping position, and in its other position to actuate it to starting position, means adapted to automatically move the start and stop member to stopping position upon the stopping of the traveling element, and eliminator means 95 adapted to render the automatic means inoperative.

43. In combination, a traveling element, a 105 rotating element, a motor for actuating the rotating element, start and stop mechanism for the motor, a start and stop member cooperatively related thereto and adapted in one position to actuate it to stopping position, and in its other position to actuate it to starting position, means adapted to automatically move the start and stop member to stopping position upon the stopping of the traveling element, eliminator means adapted to render the automatic means inoperative, and manually operable means 115 adapted to actuate the start and stop mechanism independently of the automatic means.

44. In combination, a traveling element, a 120 rotating element, a motor for actuating the rotating element, a brake-shoe adapted to stop the motor, a manually operable member adapted to operate the brake-shoe to starting and stopping position, yieldable contacting means between the brake-shoe and the manually operable member to engage the 125 parts with yielding pressure, and automatic means adapted to move the brake-shoe to stopping position upon stopping of the traveling element.

45. In combination, record rotating means, 130

sound reproducing means associated therewith, a pivoted stop member adapted to be actuated at the completion of the record, and means including a positively acting 5 latch-mechanism for preventing the operation of said stop member during the initial record playing period.

46. In combination, record rotating means, sound reproducing means associated therewith, stop mechanism for stopping the record rotating means at the completion of the record, said mechanism including a pivoted 10 stop member, and a positively-acting latch member.

47. In combination, record rotating means, 15 sound reproducing means associated therewith, means for stopping the record rotating means at the completion of the record, said means including a pivoted member, a rotating cam adapted to actuate the pivoted member, and latch means adapted to prevent actuation of the pivoted member and operative during the playing of the record, but 20 inoperative at its termination.

In testimony whereof, we affix our signatures.

GEORGE W. BEADLE,
SAMUEL KOHN.

Certificate of Correction.

It is hereby certified that in Letters Patent No. 1,430,568, granted October 3, 1922, upon the application of George W. Beadle, of Stamford, Connecticut, and Samuel Kohn, of New York, N. Y., for an improvement in "Automatic Stops," errors appear in the printed specification requiring correction as follows: Page 2, line 80, for the word "flange" read *finger*; page 3, line 44, for the word "skirt" read *sleeve*; and that the said Letters Patent should be read with these corrections therein that the same may conform to the record of the case in the Patent Office.

Signed and sealed this 5th day of December, A. D., 1922.

[SEAL.]

KARL FENNING,

Acting Commissioner of Patents.
